SLAG CONVEYER

Joseph H. James, Salt Lake City, Utah

Application August 28, 1934, Serial No. 741,865

1 Claim. (Cl. 193—11)

This invention relates to an improved apparatus characterized principally by a conveyer and especially constructed for conveying slag to a predetermined point of deposit by way of a suitable conveyer and water flotation process.

The invention is expressly designed for use in association with a blast furnace and is constructed for rendering the slag substantially buoyant and depositing it in a flowing stream of water in the conveyer in a manner to conduct it without undue obstruction to a point where it can be conveniently handled by a discharging belt or screw conveyer.

The particular structural details and their mechanical relationship will become more readily apparent from the following description and drawings.

In the drawings:

Figure 1 is a fragmentary elevational view showing the principal factors of the invention.

Figure 2 is a side elevational view of the details seen in Figure 1.

Figure 3 is a longitudinal sectional view through the same.

Figure 4 is a cross sectional view of the line 4—4 of Figure 3.

Figure 5 is a cross section on the line 5—5 of Figure 3.

Figure 6 is a top plan view of the trough-like conveyer.

Figure 7 is a view of one end portion showing a slight modification in the water delivering pipe.

In Figure 1 the conventional blast furnace is designated by the numeral 8 and this includes the customary discharge spout 9 which is here shown as provided with diametrically opposite lugs 10 to accommodate the hooks 11 on the upper end of the arm portion 12 of the strap hanger 13. This strap hanger functions as a reinforcing element for the inlet end of the conveyer generally designated by the numeral 14. The conveyer is shown as including an open-top trough portion having outwardly diverging side walls 15 and 16 and a substantially flat bottom 17.

This trough merges into and is connected with the discharge pipe 18. This leads to the conveyer belt or screw conveyer (not shown). At the intake end of the trough is a rectangular hole 19 which is of a length equal to the width of the flat bottom 17. Over this hole is a screen 20. The flattened end 21 of the water delivery pipe 22 connects with this screened water inlet hole 19. The water is introduced under appropriate pressure from a pump (not shown).

I wish to emphasize particularly the enlarged

flattened formation 21 of the water delivery pipe in that it tends to flatten the stream of water and to spread it evenly over the flat bottom of the trough. Also the top of the trough is open to allow the attendant to remove clinkers and obstructing particles before the suspended mass of water and slag enters the pipe 18.

Under some conditions instead of introducing water through the opening 19 in the end wall of the trough, it is introduced in the manner shown in Figure 7. Here the water delivery pipe 23 extends up beneath the intake end portion of the trough where it is wiped out in funnel-like configuration as at 24. The numeral 25 designates the screen which overlies the portion 24.

In practice the conveyer 14 is disposed in an appropriate inclined state and suspended by the hanger from the discharge spout 9 on the blast furnace 8. The slag enters the trough simultaneously with the incoming stream of water which is regulated properly. The slag is carried in suspension in the stream of water down through the trough and the pipe 18 and discharged at an appropriate point of deposit.

The upper end of the flat bottomed conveyer is arranged so that the slag will not pile back against the intake end wall of the trough causing the water to cut through or allowing the mass to freeze into cake and thus jeopardize the flow after the stream enters the closed pipe portion 18. This is prevented as is obvious, by the flattening of the stream of water at the intake end of the trough.

The plan of running the slag by water is by far the most important factor of the invention and therefore emphasized. It is understood that there has always been a fear light hot slag, like molten iron, would explode as soon as it contacted the water, but through this method of handling and distribution of water and slag, there is no danger. Instead, the slag pulverizes and bubbles, making it almost buoyant. Much of it does become so, and the expansion of the part that does not bubble, to the extent of buoyance becomes so light that the stream can easily carry it with a reasonable fall, or it may be pumped at any angle with slightly greater head pressure at the intake end of the trough, for instance, a pressure which would be sufficient to carry silt.

This improved combination of details combined with the centrifugal pump can be used on the crude slag for blast furnaces, and can and will replace the present expensive means of track-age, a locomotive, a ladle, cars and crew, with a

pipe and centrifugal pump, saving thousands of dollars in equipment, and unnecessary time of an operating crew.

It is thought that persons skilled in the art to which the invention relates will be able to obtain a clear understanding of the invention after considering the description in connection with the drawings. Therefore, a more lengthy description is regarded as unnecessary.

10 Minor changes in shape, size, and rearrangement of details coming within the field of invention claimed may be resorted to in actual practice if desired.

Having thus described the invention, what is 15 claimed as new is:

Means for conveying slag from a furnace comprising an inclined chute having a considerable

portion of its receiving end of channel shape in cross section with its top open and its bottom flat and the remaining part of the chute being of integral tubular form whereby the top of said remaining part is closed, said inlet end of the chute having a rectangular shaped opening in its upper extremity opening directly upon the bottom of the chute and which is of the same length as the width of the bottom, a water supply pipe having a rectangular shaped outlet end 10 connected to the chute and surrounding the opening, the bottom of the chute being plain to provide an even flow of the mixture of water and slag over the same, and means for discharging the slag into the channel part a slight distance below 15 the water inlet opening.

JOSEPH H. JAMES.
